ADJUSTABLE EDGE LIGHTER

Filed Dec. 11, 1930

Adolph A. Henkel
Inventor
By: Kent W. Womarly, Atty.

UNITED STATES PATENT OFFICE

ADOLPH A. HENKEL, OF RAVINIA, ILLINOIS, ASSIGNOR, BY MESNE ASSIGNMENTS, TO FARIES MANUFACTURING COMPANY, OF DECATUR, ILLINOIS, A CORPORATION OF ILLINOIS

ADJUSTABLE EDGE LIGHTER

Application filed December 11, 1930. Serial No. 501,572.

This invention relates in general to a lighting fixture particularly for bathroom and toilet cabinets, but may have a more general application wherever it can be used.

5 Among the objects of the invention are: to provide an adjustable lighting fixture which may be applied at the edges of a bathroom or other cabinet; to provide a marginal fixture which is adjustable over the top and 10 sides of a cabinet or the like; to provide a marginal cabinet fixture with adjustably movable lamps; to provide a centrally located adjustable fixture box cover; to provide a marginal fixture with slots in which 15 the lamps are slideable and to cover the slots above and below the lamps; to provide a fixture of this kind with removable knock-outs for admitting the fixture wires at the sides or top of the adjustable fixture; and 20 in general to provide the fixture herein shown and described. In the accompanying drawing,

Figure 1 is a front elevation with parts in section of a fixture in accordance with this 25 invention and applied at the edges of a cabinet;

Figure 2 is a side view of a fixture showing a part in section;

Figure 3 is a sectional view taken on the 30 line 3—3 of Figure 1;

Figure 4 is a section taken on the line 4—4 of Figure 1;

Figure 5 is a detail section taken on the 35 line 5—5 of Figure 1.

It is customary to provide lamps for bathroom and other cabinets and mirrors which extend over the top or at the sides of the cabinet in fixed position. Such illumination usually is too remote and is so improperly 40 placed and fixed in position to be of the greatest value. The present invention overcomes this objection by providing adjustable lamps at the sides of such a cabinet where their positions may be varied to obtain the desired 45 illumination.

Another feature of the present invention is that the fixture presented is adjustable and may be applied to existing cabinets of various sizes without removing them from the 50 wall and by simply connecting the conduc-

tors of this marginal fixture with the adjacent wiring or outlets.

Referring more particularly to the drawing, a bathroom or other cabinet 1 of a well known type is represented as having a hinged door 2 in the outer face of which is a mirror 3. This cabinet may have a lower shelf or compartment 4 which is not covered by the door or it may consist only of the upper portion without the compartment 4. The marginal fixture of this invention is combined with and applied directly to the upper and side edges of the cabinet, the marginal fixture being comparatively flat in shape so that if the cabinet projects slightly from the face of a wall 5 in which it is set, the marginal frame will be substantially flush with it and may appear as an extension or an integral part of the cabinet itself. The fixture comprises a pair of casings 6 and 7, preferably of metal and hollow or recessed on the under side to receive the wiring. The casings have angular extensions 8 and 9 to extend toward each other over the top of the cabinet with an adjustable center piece 10 which covers and forms a joint between the upper ends and allows a considerable lateral adjustment so that the side portions may fit cabinets of various widths. The top of this center piece 10 may be provided with a central removable portion as shown in connection with the side portions or it may have an upward extension 11 in place thereof which in turn is covered by a telescoping upward extension 12 preferably having an ornamental plate or cover box 13 for extending over and covering an electric conductor outlet box 14 which is commonly located in the wall 5 above the cabinet.

The outer sides of the casings 6 and 7 may be provided with a partially severed knock-out plug 15 as indicated more clearly in Figure 3 through which the conductors may extend instead of through the top piece 10 if it is more convenient to so connect them.

In the outer face of each side casing is a slot 16 through which extends the stem 17 of a fixture bracket 18 for supporting an electric lamp socket and an electric lamp 20. This fixture stem has an inner projection 21

to engage the inside of the slot 16 and the bracket 18 engages the outside of the slot with a spring 22 surrounding the fixture stem 17 and tending to hold the lamp support yieldingly in engagement with the slot.

In order to close the slot 16 above and below the lamp fixture in any adjusted position thereof, a thin strip or ribbon 23 is attached to the stem projection 21 and bears against the inside of the slot to close it for preventing the entrance of dirt and to present a neat and sightly appearance. Preferably the strip 23 is passed over rollers 24 at the ends of the slot so that it is moved upon them as the lamp fixture is raised and lowered, the frictional resistance also tending to hold the lamp in any adjusted position. Extending between the sides of the casing is a guard 25 which holds the rear side of the strip 23 in place and preserves a space for containing an electrical conductor 26 which extends loosely between the front and back portions of the strip 23 and between the upper and lower roller 24 to make a connection with the fixture stem 17, allowing free movement of the fixture support in the slot 16. The other portions of the conductors 26 extend through the casing and to the outlet connection.

This fixture may be attached directly to the side wall of the cabinet itself or to the wall at the edges of the cabinet by means of a fastening device such as a screw 27.

At the lower end of one or both of the side casings may be receptacles 30 and 31 for vending and receiving razor blades 32, the vending receptacle having a slot 33 for receiving a coin and the other receptacles having a slot 34 for receiving a used blade. It is also contemplated that one or both side casings may have a fixture plug 35 for receiving and forming a plug-in electrical connection.

An adjustable edge light fixture of this kind can be installed with a new cabinet or it may be applied to cabinets of various sizes after they have been installed. If desired, the side casings may also be made telescoping or adjustable in length, one portion slipping into the other as shown at the top of the cabinet, the upper section preferably being the fixed portion.

It is also contemplated that an edge light fixture of this kind may be made with side casing portions only, which are applied at the sides or edges of cabinets of the kind referred to, or the fixtures may be used separately between windows or as wall fixtures, or in any place in which lighting fixtures are commonly used. The obvious advantage of this type of fixture is that it may be adjusted to various heights and when so moved will remain in place until again moved or adjusted. Furthermore, the casings may be embedded or inserted in walls or other places where lights are desired, the slot only being

visible, and it being covered at the rear, if desired. Fixtures of this kind may be employed, for example, in Pullman cars, between adjacent windows where the frame is very narrow and it is desired to adjust the light either for reading, or in the dressing or toilet rooms.

Many other uses and applications of a lighting fixture of this kind will naturally occur to one skilled in this art.

I claim:

1. A lighting fixture for cabinets and the like, comprising a narrow marginal frame adapted to fit closely about the top and sides of a cabinet, means for adjusting the width of the frame for cabinets of different widths, and means carried by the frame for lighting a cabinet therein.

2. A cabinet lighting fixture comprising a narrow marginal frame to extend over the top and downwardly over the side edges of a cabinet and the top portion being adjustable for cabinets of different widths, and electric lamp fixtures carried by and slidable in the side portions of the frame.

3. The combination with a cabinet adapted to be inserted in a wall, and having a front mirror supporting hinged door, of a lighting fixture therefor comprising a comparatively shallow frame adapted to abut the wall at the sides and over the top of the cabinet, the top portion of the frame telescoping to adjust the width of the frame, and lamp supporting means slidably in the side portions of the frame to illuminate the mirror without obstructing the door in opening and closing it.

4. A cabinet lighting fixture comprising a narrow frame to fit about the top and sides of a cabinet, lighting means carried by the frame and an adjustable extension of the frame to extend to and cover an outlet box for the light conductors.

5. A cabinet lighting fixture comprising a narrow frame adjustable to fit about three sides of a cabinet and having a slot in the outer face of the frame, an electric fixture support movable in the slot and a cover strip carried by the fixture support to close the slot above and below the fixture support when it is moved therein.

6. An electric fixture for a wall cabinet comprising an adjustable narrow recessed frame adapted to fit closely about the top and side edges of a cabinet and having slots at the opposite sides thereof, fixture supports yieldingly movable in the slots, slot closing strips movable with the fixture supports, end rollers over which the strips are movable and conductor wires extending about the frame from a common inlet point and extending to the fixture supports between the end rollers and movable strips in a loose loop at each side of the frame to permit unobstructed movement of the fixture support.

7. A wall cabinet lighting fixture comprising a narrow frame adapted to fit closely about the top and sides of the cabinet and comprising a telescopic adjustment for fitting cabinets of different widths, fixture supports and slots in the sides of the frame in which they are slidable, and means forming a plurality of removable conductor outlets and a flexible electrical conductor to extend from any one of the outlets and form a loose connection with the fixture supports within the frame to permit unobstructed movement of the supports in the slots of the frame.
